UNITED STATES PATENT OFFICE.

DUDLEY E. LATHAM, OF NEW YORK, N. Y., ASSIGNOR TO DOUBLE GRIP GARTER COMPANY, INC., OF NEW YORK, N. Y., A CORPORATION.

DESIGN FOR A GARTER.

48,068.

Specification for Design.

Patented Nov. 2, 1915.

Application filed August 17, 1915. Serial No. 46,006. Term of patent 14 years.

To all whom it may concern:

Be it known that I, DUDLEY E. LATHAM, a citizen of the United States, residing at New York city, county of New York, and State of New York, have invented a new, original, and ornamental Design for a Garter, of which the following is a specification, reference being had to the accompanying drawing, forming a part thereof.

Figure 1 is a perspective view of a garter as it would appear in use, illustrating my new design; and Fig. 2 is a plan view thereof in a flattened out position.

I claim,

The ornamental design for a garter as shown.

DUDLEY E. LATHAM.
